(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the notebook computer in an alternate position; and,

FIG. 10 is another perspective view thereof showing the notebook computer in an alternate position.

The evenly-dashed broken lines shown in the drawings illustrate portions of the notebook computer that form no part of the claimed design. The dot-dashed lines define the bounds of the claimed design and form no part thereof.
